UNITED STATES PATENT OFFICE.

EARL MCFARLAND AND EDWARD C. CHURNING, OF SAUSALITO, CALIFORNIA.

SPARK-PLUG.

1,103,797.

Specification of Letters Patent. Patented July 14, 1914.

Application filed May 8, 1913. Serial No. 768,377.

To all whom it may concern:

Be it known that we, EARL MCFARLAND and EDWARD C. CHURNING, citizens of the United States, residing at Sausalito, in the county of Marin and State of California, have invented certain new and useful Improvements in Spark-Plugs; and we do hereby declare the following to be a full, clear, and exact description of the invention, such as will enable others skilled in the art to which it appertains to make and use the same.

This invention relates to new and useful improvements in duplex or multiple spark plugs for internal combustion engines.

As its principal object this invention aims to provide a device of this character in which the spark gap may be varied by means operable exteriorly of the engine cylinders.

A further object resides in the provision of a multiple spark plug in which the ignition of the gases may be accomplished by either a battery or a magneto current, or both.

A still further object is to provide a spark plug so constructed that the sparking point of the magneto circuit and the battery circuit may be independently adjusted exteriorly of the engine, and without necessitating the removal of the plug.

The above and additional objects are accomplished by such means as are illustrated in the accompanying drawings, described in the following specification, and then more particularly pointed out in the claims which are appended hereto and form a part of this application.

With reference to the drawings, wherein we have illustrated the preferred embodiment of our invention as it is reduced to practice, and throughout the several views of which similar reference numerals designate corresponding parts: Figure 1 is a vertical section of the preferred form of this invention. Fig. 2 is a top plan view of the preferred form. Fig. 3 is a bottom plan view of the preferred form. Fig. 4 is a vertical section of the modified form. Fig. 5 is a bottom plan view of the modified form.

Proceeding now to the description of the drawings, the preferred embodiment of this invention, as illustrated in Figs. 1, 2 and 3, includes a plug body 1, consisting of the

customary threaded bushing made of steel, brass, or bronze, reduced at its lower portion, and externally screw threaded, as at 2, in the usual manner for permitting the bushing to be threaded into a hole tapped 60 in the engine cylinder. The bushing 1 is cored in the usual manner to provide a pair of electrode receiving passages, which, in this invention, are downwardly convergent. The upper portion of each of the electrode 65 passages is enlarged and outwardly off-set as regards its angular relation to the longitudinal axis of the bushing. Inasmuch as each electrode and the insulation therefor is similar in construction and arrangement, 70 it is deemed necessary to describe only one of the elements. At the juncture of the enlarged portion 3 with the lower reduced portion 4 of the electrode bore, the passage is enlarged to provide an annular recess, 75 as indicated at 5. An insulating tube 6, formed of any standard material such as porcelain, mica, or steatite, is arranged in the reduced portion 4 of the bore, and carries at its upper terminal an annular laterally extending flange 7 which is disposed to rest on the bottom face of the annular recess 5, as will be observed by reference to Fig. 1. Extending upwardly through the enlarged portion 3 is an insulating tube 8, 85 carrying at its lower terminal a lateral annular flange 9 which, in the preferred embodiment, is molded integrally with the member 7. There is thus provided an annular chamber at the junction of the members 7 and 9, wherein is arranged a collar 10 formed at the junction of the upper and lower sections 11 and 12, respectively, of the electrode. After the electrode and its insulating tube have been arranged in the 90 receiving passage, a bushing 13, provided with the usual nut head and externally screw threaded reduced portion, is slipped over the electrode, and is threaded into the enlarged portion 3 of the passage. It will 100 be readily observed that by threading the member 13 into severe engagement with the member 9, that the insulating tube and the electrode are held in secure fixed position. The upper portion of the electrode 105 is threaded in the usual manner and carries the customary binding nuts 14 and 15, the member 15 being insulated from the bushing by an insulating washer 16.

Centrally of the bottom face of the re- 110

duced portion 2 of the plug body is mounted a platinum ground point 17 which may be threaded into the member 2 to facilitate the removal of a worn point, and the substitution of a new ground point. The lower projecting terminals of the electrodes carry platinum points, as indicated at 18. These members 18 are bent inwardly in the direction of the member 17, and may be adjusted to produce the desired spark gap previously to the application of the plug to the cylinder.

From the foregoing it will be observed that the preferred form of this invention provides a spark plug in which a battery circuit and a magneto circuit may be simultaneously or selectively employed. In this connection it is to be noted that the positive battery wire may be attached to one electrode and the positive magneto wire to the other electrode, the negative of each circuit being grounded in the usual manner.

In the modified form of this invention, illustrated in detail in Figs. 4 and 5, there has been provided a spark plug in which the length of the spark gap may be exteriorly adjusted to provide a means for quickly remedying inefficient sparking, frequently resulting from worn points or improper primary adjustment of the spark gap. To this end, the flanges 7 and 9 of the preferred form which are designated by the numerals 20 and 21, respectively, in the modified form, and are molded separately, as will be noted by reference to Fig. 4, thus producing two separate insulating tubes 22 and 23. Reference now being had to Fig. 5, it will be observed that the platinum points 24 and 25 of the electrodes are of greater length than the points in the preferred form, and that the electrodes 26 and 27 are arranged at a greater distance from the ground points 28. The construction of the remaining features of the modified embodiment are similar to the corresponding features of the preferred embodiment.

It will be apparent that by merely forming the insulation into separate tubes 22 and 23, that the bushings 29 of the modified form may be partially withdrawn from their receiving bores, to permit the electrodes 26 and 27 to be rotated. As indicated by dotted lines in Fig. 5, the rotation of the electrodes will act to increase or diminish the length of the spark gap. After the electrodes have been manipulated, to produce the desired spark gap, the bushing 29 is again threaded into severe engagement with the member 21 of the tube 23, thus clamping the collar 30 of the electrode and holding the electrodes in adjusted position. The manipulation of the bushing 29 and the electrodes, during the adjustment of the spark gap, will be apparent upon reference to Fig. 4, in which the electrode on the left

hand is shown in position for adjustment, while the electrode on the right is shown in clamped adjusted position.

It is desirable to emphasize the fact that the provision of the multiple circuit plug in which the spark gaps are exteriorly adjustable, is regarded as a feature of utmost importance. The importance of the feature above noted will be apparent when it is considered that inasmuch as the E. M. F. of a magneto circuit is greater than the E. M. F. of a battery circuit, (unless the current of the latter circuit be passed through a spark coil of unusual strength,) it is necessary to provide a smaller spark gap for the battery circuit.

In reduction to practice, we have found that the form of our invention, illustrated in the drawings and referred to in the above description, as the preferred embodiment, is the most efficient and practical; yet, realizing that the conditions concurrent with the adoption of this device will necessarily vary, we desire to emphasize the fact that various minor changes in details of construction, proportion and arrangement of parts may be resorted to, when required, without sacrificing any of the advantages of our invention, as defined in the appended claims.

What is claimed is:

1. A spark plug including a cored body member, a ground point threaded in said body member, said body member being provided with a pair of downwardly convergent electrode bores, each of said bores being enlarged and internally screw threaded at its upper terminal, an annular recess formed at the junction of the enlarged portion of the bore and the lower reduced portion, an insulating tube for said lower portions of each bore, an annular flange formed on said tube and arranged in said annular recess, an insulating tube for said upper enlarged portion of each of said bores, an annular flange carried by said second tube and arranged in said annular recess, a pair of electrodes arranged in said bores, a collar carried by each of said electrodes and mounted between the said tube flanges, and a clamping bushing for each of said electrodes, said bushing being threaded in said enlarged upper terminal of said passages.

2. A spark plug including a body member, a pair of electrodes arranged in said body member, insulating tubes for each of said electrodes, laterally extending platinum points for each of said electrodes, a ground point threaded in said body portion and arranged between the said electrodes, said electrodes being adapted to rotation for varying the distance of the points from the ground point, and means for clamping the electrodes in adjusted position.

3. A spark plug comprising a body por-

tion having a pair of downwardly converging electrode bores formed therein, a pair of electrodes mounted within said bores, insulating tubes for each of said electrodes mounted within the bores, lateral points for each of said electrodes disposed in spaced relation to each other, a ground point removably secured to said body portion between the electrode points, means for preventing longitudinal movement of said electrodes relative to the body portion and permitting rotary movement and means for clamping the electrodes in adjusted position.

4. A spark plug comprising a body portion having a pair of downwardly converging electrode bores formed therein, an electrode mounted within each of said bores, an

insulating tube for each of said electrodes, a laterally extending point formed integral with each of said electrodes, a ground point secured to said body portion adjacent the electrode points, means for preventing longitudinal movement of the electrode relatively to the body portion and for permitting rotary adjustment of the electrodes and means for clamping the electrodes in adjusted position.

In testimony whereof we affix our signatures in presence of two witnesses.

EARL MCFARLAND.

EDWARD C. CHURNING.
